METHOD OF PREPARING MOISTUREPROOF WRAPPINGS FOR PERISHABLE ARTICLES

Charles Nicollé, Gentilly, France

Original application January 21, 1946, Serial No. 642,461. Divided and this application March 17, 1949, Serial No. 81,864. In France August 4, 1944

Section 1, Public Law 690, August 8, 1946
Patent expires August 4, 1964

6 Claims. (Cl. 53—5)

1

This application is a division of my copending application Serial No. 642,461 filed on January 21, 1946, now Patent No. 2,512,367, dated June 20, 1950.

This invention relates to the packaging of perishable products, and more especially products such as chemical, pharmaceutical preparations and food products which may be adversely affected by atmospheric influences such as moisture in sheets of plastic material, such as for instance cellulose acetate which can be deformed by pressure or otherwise.

It is an object of this invention to provide means for protecting products which are likely, when stored, to deteriorate when they are exposed to moist air.

In order to package such products, it has been proposed to coat the sheets of plastic material used as a wrapping with a moisture-proof varnish. However, if such varnish is applied to the inner side of the sheet, it is liable to impart to the product an unpleasant taste or to act on it in some other way. If on the contrary it is applied on the outside, it is liable to become damaged in the course of manipulation and consequently not to retain its moisture-proofing effect.

It has also been proposed to use composite sheets comprising an intermediate moisture-proof layer (latex, varnish or the like) enclosed between two sheets of plastic material. However, such composite sheets still possess certain disadvantages when they are used for the packaging of products particularly sensitive to moisture. If the wrapper is not applied closely to the product, it leaves around the latter an atmosphere which may contain a high amount of moisture, which in the case of certain products may still increase and which may have a disintegrating action or other detrimental effect on the product. Moreover, wrappers made according to this method are little suited for products in powder form, for pasty and soft products or for irregularly shaped products.

In my French Patent No. 851,279, which corresponds to a prior application for patent of the United States, Serial No. 293,601 filed September 6, 1939, published by the Alien Property Custodian on May 11, 1943, and now abandoned, I proposed, in order to remedy these disadvantages, to manufacture moisture-proof wrappers from cellulose acetate comprising recesses formed in accordance with the size and volume of the article to be packaged, and in which the wrappings were constituted by two layers of cellulose acetate between which was inserted a layer of moisture-proof varnish or the like. These composite sheets

were then shaped by pressure to form therein recesses corresponding to the shape of the products to be packaged which required the intermediate moisture-proof layer to possess the plastic qualities necessary to permit the formation of such depressions without tearing, while retaining its moisture-proof qualities. However, owing to stretching, in the shaping operation, certain points of the sheet are thinned down considerably and there is the risk of the intermediate waterproof layer being torn and admitting moisture at these places.

It is an object of the present invention to avoid this by making it possible to carry out the moisture-proofing of the wrapper subsequently, that is to say after the packaging of the product, and to permit the use of the waterproofing layer to be limited, in case of need, to the strictly indispensable portions, and finally to permit the use of varnishes which do not present the peculiar qualities of elasticity heretofore required.

According to my invention, in order to obtain a waterproof wrapper from sheets of cellulose acetate (or equivalent plastic materials) provided with recesses intended to contain the products to be wrapped in one at least of the components of the wrapper, two sheets of plastic material are formed with such recesses and a layer of moisture-proof varnish and adhering to the plastic material is applied between the two sheets and the depressions of one sheet are then nested in those of the other sheet.

The uniting of the two sheets with the layer of moisture-proof varnish between them may be effected before or after the articles to be packaged have been placed in the cup-shaped depressions which are then closed by cementing to the combined sheets a covering also consisting of a combination of two sheets of plastic material with a moisture-proof varnish between them, which may be flat or may be formed with similar cup-shaped depressions.

In the drawings affixed to this specification and forming part thereof several forms of packages produced in accordance with this invention are illustrated diagrammatically by way of example.

In this drawing—

Figures 1 to 4 show various forms of wrappers waterproofed conformably to my invention;

Figures 5 to 8 show other forms in which a clearance is left between the two sheets forming one of the two components of the wrapper;

Figure 9 shows still another form in which the waterproofing varnish is only applied locally;

Figure 10 illustrates a package in which several

2

cells are contained within another larger waterproofing cell;

Figures 11 and 12 illustrate the two principal ways of producing wrappers according to the present invention, Figure 11 showing moisture-proofing carried out prior to packaging and Figure 12, packaging carried out prior to moisture-proofing.

As will be seen in Figures 1 to 4, between an inner sheet 1 and an outer sheet 2 of cellulose acetate (or an equivalent plastic material) previously formed with depressions is placed a layer 3 of moisture-proofing varnish (which is represented as being applied, for instance, to the outer sheet 2).

This assembly of two sheets 1 and 2 previously formed with depressions and subsequently nested in one another with a waterproof varnish 3 between them constitutes one of the two components of the wrapper. It may be completed, for the closing of the wrapper, either by a similar symmetrical assembly 1a-3-2a (Fig. 1) or 1'a-3-2'a (Fig. 4), or by a plane component formed of two plane sheets 1b and 2b of plastic material with the interposition of a moisture-proof varnish 3 (Fig. 2), or by a component 1c-3-2c similar to the complementary component 1a-3-2a, but with shallower depressions entering into engagement with the deeper depressions of component 1-3-2 (Fig. 3).

Of course, the depressions may be of any shape whatever, both in cross section and in plane view, according to the shape, the nature and the volume of the product to be wrapped. Figures 1 to 3 concern, for instance, the wrapping of cylindrical pills or of compressed tablets, whereas Figure 4 more particularly concerns the packing of spherical pills. Powders, granules, pasty or gelatinous products or even liquids might likewise be packaged.

It should be noted that the coat of moisture-proof varnish 3 may be applied either inside the outer sheet 2 of each of the two components of the wrapper (Figures 1 to 4), or on the outside of the inner sheet 1 (Fig. 12).

The two sheets 1 and 2 need not be in contact all over their surface (Figures 1 to 4). If desired, a certain space 5, forming an air cushion, may be left between the two sheets 1 and 2, either all around the inner depression (Fig. 5), or only above (or beneath) the bottom of each inner depression (Fig. 6). As shown in Figures 7 and 8, the general shape of the two sheets 1 and 2 of each component of the wrapper may differ in such a manner as to leave a clearance 5' between the two sheets. For instance, as in Figure 7, the inside sheet 1d may comprise truncated cone depressions, whereas the outer sheet 2d comprises cylindrical depressions. In Figure 8, as one of the components of the wrapper, an inner sheet 1a is combined with an outer sheet 2e formed with bulging depressions, and for the other component of the wrapper an inner sheet 1c is used, provided with depressions of little depth engaging in the depressions of sheet 1a and an outer flat sheet 2b. In all cases, the layer of moisture-proof varnish 3 is inserted between the two sheets of each component of the wrapper and the outer sheets are always, in addition, joined to the inner sheets by their plane portions.

The joining of the outer sheet 2 to the inner sheet 1 may be effected by the application of pressure and heat and in case of need with the addition of a cement or a suitable solvent to make them adhere solidly to one another, either

all over their surface or only at certain sections. The wrappers represented in the various Figures 5 to 8 constitute not only moisture-proof wrappings, but, owing to the air cushions 5, 5' or 5'', also shock-proof packages.

In the package of Fig. 9 instead of applying the coating of varnish 3 to the entire inner surface of outer sheet 2a, varnish is only applied to the cup-shaped depression, which permits of welding the flat sections of cellulose acetate together.

According to Fig. 10, several depressions formed in the inner sheet 1a are protected by a single larger depression in the outer sheet 2f, a coat of moisture-proof varnish 3 being inserted between the two sheets after the shaping of the depressions said coat being applied to the outside of the inner sheet or, as has been represented in Fig. 10, inside the outer sheet.

In Figures 11 and 12 two ways of proceeding in order to manufacture a moisture-proof packing from sheets of cellulose acetate or other equivalent plastic are illustrated.

In Figure 11, the inner sheet 1a and the outer sheet 2a are formed with depressions and are then united by interposing between them the moisture-proof varnish 3. Two such assemblies with the products 4 to be wrapped between them are joined and secured to one another by their plane portions.

According to Figure 12, a wrapper of plastic material is first made from two depressed sheets or a depressed sheet and a plane sheet or one formed with shallower depressions turned over and engaging within the deeper depressions of the other sheet, the products 4 being placed in the depressions and the sheets 1a being joined by their plane portions. The wrapper being thus constituted in the usual manner, the coat of waterproofing varnish is applied either outside the wrapper, as has been shown in Figure 12, or inside the outer protecting sheets 2a, as in the case for instance for the kind of packings shown in Figures 1 to 4 and on this wrapper is placed the second outer sheet 2a with the coat of varnish 3 interposed, the uniting and securing of the outer and inner sheets 1a and 2a being carried out by any suitable means (pressure, heat, or the use of a suitable cement or solvent).

This way of proceeding makes it possible, if desired, to carry out the waterproofing of the packing only if it is indispensable. For instance, a product moderately sensitive to moisture will be packed according to the usual method, between two single depressed sheets for the purpose of delivering it for consumption in a country enjoying a temperate climate, the protection afforded by the plastic material alone being sufficient to maintain the product in sound condition during the few weeks or months which may elapse between manufacture and consumption. If it is desired to ship this same product in the same wrapper to a country with a hot or damp climate and to retain its qualities over a long period of time, the above packing is then covered with two protective outer sheets or depressed pellicules previously coated with waterproofing varnish.

In any case, whatever the mode of preparation adopted, a package is obtained the moisture-proofness of which is ensured with certainty, since the coat of moisture-proof varnish applied after deformation of the wrapping material runs no risk of becoming weakened, of cracking, or of tearing or even of breaking, at certain points, even if, for said intermediate layer, a material is employed which does not possess the same

plastic qualities as the sheets intended to form the wrapper. There is thus a far greater choice of varnish available, since the latter need not be really plastic, but only slightly pliable. It will, in particular, be possible to utilize varnishes the handling of which is very simple and offers no danger, and comparatively cheap varnishes. The varnishes may be selected among the very transparent ones, there being no risk of their transparency deteriorating in the course of the operations of shaping of the depressions (under the influence of heat for instance), since the varnish is applied only subsequently.

According to this invention, it is possible to arrange between the inner and the outer sheets a coating of varnish of any desired thickness. It is also possible to apply the varnish with a spray-gun, using suitable stencil-plates for the purpose of depositing a thicker coating on the bottom of the depression. It is even possible to deposit it in the depressions and not on the plane portions, as shown in Figure 9.

To all these advantages are added those resulting from the interposition of the moisture-proof coating between two sheets of plastic material: the absence of any influence of this coating on the packed product itself and the protection of said coating by the outer sheets of plastic material, the varnish never being in contact with the tools or parts of machines utilized for the manufacture of the wrappers, during the closing operations.

Wrappers according to the invention may comprise striated plane portions, lines of perforations for the separation of the individual packages, tearing points for the opening of the individual cells, etc. in short, all the improvements applicable to wrappings of this nature. The new process may also be combined with the system in which a non-cemented zone is reserved around the base of the depression.

Modifications might of course be made in the details of embodiment of the above packings described as examples, without the general economy of my invention being thereby affected.

I claim:

1. The method of making a moistureproof package containing at least one article comprising the steps of molding a pair of inner sheets of moldable plastic wrapping material to provide in a first one of said inner sheets at least one recess surrounded by plane portions, said recess being adapted to receive said article, and to provide in the second inner sheet a cover portion for said recess surrounded by corresponding plane portions, molding a pair of outer sheets of similar material with respective recess and cover portions conforming generally to the contours of the recess and cover portions of said inner sheets; coating with a moistureproof varnish those surfaces of the conforming portions of one pair of said sheets which will be adjacent the conforming portions of the other pair; assembling said outer sheets in juxtaposition to the respective inner sheets with said layers of moistureproof varnish intervening, thereafter sealing at least parts of said outer sheets to corresponding parts of said inner sheets; placing said article in said recess, and sealing the plane portions of said inner sheets together to enclose said article.

2. The method of making a moistureproof package containing at least one article comprising the steps of molding a pair of inner sheets of moldable plastic wrapping material to provide

in a first one of said inner sheets at least one recess surrounded by plane portions, said recess being adapted to receive said article, and to provide in the second inner sheet a cover portion for said recess surrounded by corresponding plane portions, molding a pair of outer sheets of similar material with respective recess and cover portions conforming generally to the contours of the recess and cover portions of said inner sheets; 5 coating with a moistureproof varnish those surfaces of the conforming portions of one pair of said sheets which will be adjacent the conforming portions of the other pair; assembling said outer sheets in juxtaposition to the respective inner sheets with said layers of moistureproof varnish intervening, thereafter sealing at least parts of said outer sheets to corresponding parts of said inner sheets; and thereafter placing said article in said recess, and sealing the plane portions of said inner sheets together to enclose said article.

3. The method of making a moistureproof package containing at least one article comprising the steps of molding a pair of inner sheets 10 of moldable plastic wrapping material to provide in a first one of said inner sheets at least one recess surrounded by plane portions, said recess being adapted to receive said article, and to provide in the second inner sheet a cover portion for said recess surrounded by corresponding plane portions, molding a pair of outer sheets of similar material with respective recess and cover portions conforming generally to the contours of the recess and cover portions of said inner sheets; 15 placing said article in said recess, and sealing the plane portions of said inner sheets together to enclose said article; thereafter coating with a moistureproof varnish those surfaces of the conforming portions of one pair of said sheets which will be adjacent the conforming portions of the other pair; assembling said outer sheets in juxtaposition to the respective inner sheets with said layers of a moistureproof varnish intervening, thereafter sealing at least parts of said outer sheets to corresponding parts of said inner sheets.

4. The method of making a moistureproof package containing at least one article comprising the steps of molding a pair of inner sheets 20 of moldable plastic wrapping material to provide in a first one of said inner sheets at least one recess surrounded by plane portions, said recess being adapted to receive said article, and to provide in the second inner sheet a cover portion for said recess surrounded by corresponding plane portions, molding a pair of outer sheets of similar material with plane portions conforming generally to the plane portions of said inner sheets and with respective recess and cover portions 25 deeper than the recess and cover portions of said inner sheets; coating with a moistureproof varnish those surfaces of the conforming portions of one pair of said sheets which will be adjacent the conforming portions of the other pair; assembling said outer sheets in juxtaposition to the respective inner sheets with said layers of moistureproof varnish intervening, thereafter sealing at least parts of said outer sheets to corresponding parts of said inner sheets; placing said article in the recess of said first sheet and sealing the plane portions of said inner sheets 30 together to enclose said article.

5. The method of making a moistureproof package containing at least one article comprising the steps of molding a pair of inner sheets

of moldable plastic wrapping material to provide in a first one of said inner sheets at least one recess surrounded by plane portions, said recess being adapted to receive said article, and to provide in the second inner sheet a cover portion for said recess surrounded by corresponding plane portions, molding a pair of outer sheets of similar material conforming closely to the contours of said inner sheets; coating with a moistureproof varnish those surfaces of the conforming portions of one pair of said sheets which will be adjacent the conforming portions of the other pair; assembling said outer sheets in juxtaposition to the respective inner sheets with said layers of moistureproof varnish intervening, thereafter sealing the plane portions of said outer sheets to the corresponding plane portions of said inner sheets; placing said article in said recess, and sealing the plane portions of said inner sheets together to enclose said article.

6. The method of making a moistureproof package containing a plurality of articles comprising the steps of molding a pair of inner sheets of moldable plastic wrapping material to provide in a first one of said inner sheets a plurality of recesses surrounded by plane portions, each said recess being adapted to receive one of said articles, and to provide in the second inner sheet cover portions for said recesses surrounded by corre-

5 sponding plane portions, molding a pair of outer sheets of similar material with respective recess and cover portions each adapted to nestingly receive a plurality of the recess and cover portions of said inner sheets; placing said articles in said article-receiving recesses of said one inner sheet and sealing the plane portions of said inner sheets together to enclose said articles; thereafter 10 coating with a moistureproof varnish those surfaces of the opposed recess and cover portions of one pair of said sheets which will be adjacent the recess and cover portions of the other pair; assembling said outer sheets in juxtaposition to the respective inner sheets with said layers of moistureproof varnish intervening, and thereafter sealing at least parts of said outer sheets to corresponding parts of said inner sheets.
